UNITED STATES PATENT OFFICE

2,440,120

FOLDING BOX MACHINE

William A. Ringler, Wayne, Pa., assignor to The
Gardner-Richardson Company, Middletown,
Ohio, a corporation of Ohio

Application October 19, 1945, Serial No. 623,243

5 Claims. (Cl. 93—53)

1

This invention relates to machines for the mechanical closing of folding boxes or cartons and has particular application to machines for the handling of cartons comprising a body portion and a cover hinged to the body portion which after filling of the carton is telescoped over the side walls of the body portion.

The present invention provides an automatic machine for the closing of hinged cover cartons at high production speeds and is particularly suited for the handling of cartons set up from prefabricated flat collapsed blanks.

The present invention is concerned with a machine or machine section which receives for closing cartons which have previously passed through a filling machine. The filled cartons are advanced through the closing machine at a continuous rate of speed while successive carton closing operations are being performed.

Machines embodying the present invention are particularly suited for the handling of cartons consisting of a carton body having a bottom panel and side, front and back walls connected to the bottom panel, and a carton cover comprising a top panel hinged to the back wall and front and side flange panels connected to the top panel. Automatic locking means may be provided for locking the carton cover in carton closed position and may comprise a lock flap hinged to the front wall and abutment means on the front flange panel engageable by the lock flap when the cover is swung over the body portion of the carton. Such cartons may be set up from collapsible prefabricated blanks frequently provided with fold lines extending across the side walls of the carton body and the side walls to facilitate collapsing of the prefabricated carton blank into flat condition.

The present invention provides a machine particularly adapted for the handling of such collapsible cartons in a manner to prevent recollapsing or distortion of the carton which would interfere with the rapid handling of the cartons during the closing operations.

The various objects and advantages of this invention will appear more fully from the detailed description which follows accompanied by drawings showing for the purpose of illustration a preferred embodiment of the invention.

The invention also consists in certain new and original features of construction and combination of parts hereinafter set forth and claimed.

Although the characteristic features of this invention which are believed to be novel will be particularly pointed out in the claims appended

2

hereto, the invention itself, its objects and advantages, and the manner in which it may be carried out may be better understood by referring to the following description taken in connection with the accompanying drawings forming a part thereof, in which

Fig. 1 is a perspective view of a prefabricated collapsed flat ready glued carton blank ready for expansion into hollow carton form, filling 10 and closing on machines embodying the present invention;

Fig. 2 is a perspective view of a hollow unfilled carton expanded from the blank shown in Fig. 1;

Fig. 3 is a perspective view of the closed carton; 15 Fig. 4 is a side elevational view, partly in section, of a carton closing machine embodying the present invention;

Fig. 5 is a plan view of the machine shown in Fig. 4; and

20 Figs. 6 to 9 are perspective views illustrating successive operations performed by the machine shown in Figs. 4 and 5.

In the following description and in the claims 25 various details will be identified by specific names for convenience. The names, however, are intended to be as generic in their application as the art will permit.

Like reference characters refer to like parts in the several figures of the drawings.

30 In the drawings accompanying, and forming part of, this specification, certain specific disclosure of the invention is made for the purpose of explanation, but it is understood that the details may be modified in various respects without departure from the principles of this invention and that the invention may be applied to other structures than the ones shown.

Referring to the drawings, Figs. 1 to 3 illustrate a form of carton which may be handled 40 on machines embodying the present invention, it being understood that cartons of different construction may equally well be handled on the machine. In Figs. 1 to 3 only the principal structural parts of the carton are illustrated. 45 Such as glue flaps or glue seams being omitted for the sake of clearness, such details being not essential for an understanding of the present invention.

A carton blank A is shown in Fig. 1 in the form in which it may be delivered to a product manufacturer or packer from a paper box manufacturer. The blank A is ready glued and folded and collapsed into flat form so as to require only a minimum of space. Its construction is best understood by first referring to Fig.

2 showing a hollow carton A' set up from the collapsed carton blank A. The carton comprises a body portion consisting of a bottom panel 11, side walls 12 and 13, a front wall 14 and a back wall 15. The cover portion of the carton comprises a top panel 16 hingedly connected to the back wall 15 along a hinge line 17, a front flange panel 18 and side flange panels 19 and 20.

Cartons may be equipped with automatic means for locking the carton cover in carton closed position. Such locking means comprise, in the illustrated embodiment, a lock flap 21 hinged to the front wall 14 along a hinge line 22 and abutment flaps 23 and 24 providing an abutment edge 25. The abutment flaps are secured to the inside surface of the front flange panel 18 and are so arranged that the abutment edges 25 of the flaps 23 and 24 move into edge to edge position with the free edge 26 of the lock flap 21.

Fold lines 27, 28, 29 and 30 extend across the side walls of the body portion and further fold lines 31 and 32 extend across the side flange panels 19 and 20. These fold lines permit collapsing of the blank into the flat form illustrated in Fig. 1.

Fig. 1 shows the blank in collapsed condition, the back wall 15 and the top panels 16 lying topmost. The side flange panels 19 and 20 are folded at their respective fold lines 31 and 32 and the side walls 12 and 13 are folded at their respective fold lines 27, 28, 29 and 30.

A knowledge of the construction and operation of machines or equipment for the expanding of the collapsed flat blank A of Fig. 1 into hollow carton form A' of Fig. 2 is not required for an understanding of the present invention. Such machines form the subject matter of separate inventions and applications for Letters Patent. Suffice it to say that automatic machines may be employed for expanding and opening the carton into the position shown in Fig. 2 and that additional equipment is provided for filling the carton with merchandise, or food, as the case may be. The set up, filled carton then reaches the automatic closing machine or machine unit to which the present invention relates. The closing machine aligns the cover of the carton with the carton body and moves the cover into carton closed position while the carton moves along at an even, rapid rate of advance without acceleration or deceleration whereby dislocation or spilling of the contents is prevented.

The closed carton is shown in Fig. 3, the locking means being indicated by broken lines. The lock flap 21 is folded about its hinge line 22 over the outside surface of the front wall 14 and engages with its free edge 26 the abutment edges 25 of the abutment flaps 23 and 24.

The machine for closing the carton comprises a base 33 providing a substantially horizontal table or platform 34 over which an endless conveyor 35 travels. The conveyor consists of a belt 36 having pairs of lugs 37 and 38 mounted thereon so spaced as to receive a carton between each pair of lugs. The lugs 37 will be termed leading lugs and engage the side wall of the carton which is frontmost with respect to the direction of travel of the carton and the lugs 38 will be termed trailing lugs since they engage the side wall of the carton which is rear most with respect to the direction of advance. The conveyor belt 36 is trained around suitable power driven drums near the ends of the machine, a drum 39 being visible near the dis-

charge end of the machine. The drum 39 is mounted on a shaft 40 to which power is supplied in any suitable manner, for example by a belt pulley 41. The shaft 40 turns in bearings 42 and 43 and has connected to its other end a gear 44 for driving elements of the machine which will later be described.

The conveyor 35 runs from or through the carton filling machine or unit carrying filled cartons to the carton closing machine or unit, the covers being substantially in the position as shown in Fig. 2. The cartons are firmly held between pairs of lugs, the leading lug 37 engaging the leading side wall 12 and a trailing lug 38 engaging the trailing side wall 13.

As the filled carton enters the closing machine or unit the carton cover, more particularly the top panel 16, is engaged at station I by the end portion 45 of a sweep or plow 46 which folds the carton cover towards the carton body as shown at the right hand side of Fig. 4.

The carton then advances towards the discharge end of the machine, and moves at a station II within the reach of a further sweep or plow 47 which engages the upstanding lock flap 21 and folds it downwardly over the outside surface of the front wall 14. This folding operation is shown in Fig. 7 on a larger scale. It will be noted that during these operations the cover of the carton is still in semi-collapsed condition, its side walls 19 and 20 being creased at the fold lines 31 and 32 due to the stiffness of the stock from which the carton is made.

Means are accordingly provided for straightening the side flange panels 19 and 20 of the cover portion before the carton cover is folded into carton closed position by an intermediate section 48 of the sweep 46 engaging the top panel 16 at a station III.

As each carton approaches station III a yieldable arm 49 engages the leading side flange panel 19 of the cover and causes its two panel portions to straighten out at the fold line 31. The arm 49 is preferably made of spring material and mounted in the machine at 50.

Substantially simultaneously or immediately thereafter a further arm 50 movable in the direction of advance of the carton engages the trailing side flange panel 20 and straightens its two portions at the fold line 32. The operation of the arms 49 and 50 fully erects the carton cover preparatory to the movement or folding of the carton cover into carton closed position by the section 48 of the sweep 46.

The arm 50 is preferably made of resilient material and secured to a boss 51 on a shaft 52 rotatable in bearings 53 and 54. One end of the shaft 52 extends through the bearing 53 and carries a sprocket gear 55 secured at 56. A sprocket chain 57 is trained around the sprocket gear 55 and a further sprocket gear 58. The sprocket gear 58 is integral with a spur gear 59 meshing with a gear 44 and is rotatably mounted on a stub shaft 60 on the machine base 33. The ratio of transmission of the drive of the rotatable arm 50 and its timing with respect to the conveyor 35 is such that the arm 50 engages the trailing side flange panel 20 of each carton as it moves through the station III immediately prior to the moving of the carton cover over the corresponding side and front walls of the carton body in telescopic manner.

When the carton leaves station III and while still under action of arms 49 and 50 the terminal portion 61 of the sweep 46 swings the carton cover

down fully over the side walls 12 and 13 and the front wall 14.

After disengagement of the arms 49 and 50 from the side flange panels 19 and 20 of the cover, the body portion of the carton pilots and guides the carton cover further until it reaches the fully closed position in which the free edge 26 of the lock flap 21 engages the abutment edges 25 shown in Fig. 3.

The closed carton leaving station IV of the machine is ready for packing into large containers, wrapping into a sheet of protective material such as Cellophane or wax paper, or for further processing of its contents, for example quick freezing in the case of frozen food products.

The conveyor 35 may be used for transporting the closed cartons to other locations for such further handling as may be desired or the cartons may be removed from the conveyor in any suitable manner. Since, however, the further handling of the closed cartons is not important for an understanding of the present invention, the conveyor and the machine platform are shown broken off at 62.

During the advance of the carton through the carton closing machine or unit the side walls of the carton body are firmly held between pairs of conveyor lugs 31 and 38 insuring positive advance of the individual cartons at predetermined intervals along the conveyor. Lateral movement of the carton may be prevented by lateral guide rails 63 and 64 engaging the front and back wall 14 and 15 of the carton respectively.

The invention thus provides an efficient machine for the closing of filled cartons at rates of 120 cartons a minute and over. The main feature of the invention resides in the fact that the cartons are advanced continuously without change of speed or change of direction, whereby dislocation and spilling of contents is effectively prevented. The cartons are securely guided throughout their travel through the machine and the carton cover parts are so guided as to insure accurate engagement with the carton body. This is a feature of particular importance in the handling of cartons set up from collapsed flat blanks since such cartons tends to return to a collapsed or semi-collapsed condition by reason of the previous folding of the blank. The present machine corrects such tendency of the carton and makes possible the handling of cartons at an extremely rapid rate without danger of failure.

Obviously the present invention is not limited to the handling of cartons provided with automatic locking means as are provided in the illustrated carton embodiment. Also the invention is not restricted to the use of cartons made from previously collapsed carton blanks since the features of positive guidance of the carton cover over the carton body are equally valuable in the handling of cartons of the non-collapsible type. The arms 49 and 50 engaging the leading and trailing side flange panels of the cover insure proper alignment of the cover with respect to the carton body and prevent misalignment which obviously would lead to damage of the carton and interfere with the operation of the machine.

It will be evident that various changes, additions, omissions and modifications may be made in the illustrated structure without departing from the fundamental principles and advantages of the invention. For example the conveyor belt 36 may be provided with cleats or other means for insuring a positive drive by the drums 39 and proper timing. Also the conveyor may be in the

form of an endless chain. Such details are obvious to persons skilled in the art and are omitted from the accompanying drawings for the sake of clearness.

5 What is claimed is:

1. A machine for the automatic closing of open cartons consisting of a carton body comprising a bottom panel, side walls, and a front and a back wall connected to the bottom panel; a carton cover hinged to said back wall, and front and side flange panels connected to the top panel, which carton in the collapsed condition has its cover side flange panels outfolded and its cover front flange panel infolded; and automatic locking means comprising a lock flap hinged to the front wall, and abutment means on the front flange panel, the machine comprising, in combination, an endless conveyor having lugs thereon adapted to engage said side walls; a sweep along the path of said conveyor for engaging and downfolding said cover into carton closed position; a first yieldable arm for engaging and bearing against the leading side flange panel, and a second arm moved in the direction of advance of

10 said conveyor engaging and bearing against the trailing side flange panel during the engagement of the cover by said sweep.

15 2. A machine for the automatic closing of open cartons consisting of a carton body comprising a bottom panel, side walls, and a front and a back wall connected to the bottom panel; a carton cover hinged to said back wall, and front and side flange panels connected to the top panel, which carton in the collapsed condition has its cover side flange panels outfolded and its cover front flange panel infolded; and automatic locking means comprising a lock flap hinged to the front wall, and abutment means on the front flange panel, the machine comprising, in combination, an endless conveyor having lugs thereon adapted to engage said side walls; a sweep along the path of said conveyor for engaging and downfolding said cover into carton closed position; a first yieldable arm for engaging and bearing against the leading side flange panel, and a second arm moved in the direction of advance of

20 said conveyor engaging and bearing against the trailing side flange panel during the engagement of the cover by said sweep.

25 3. A machine for the automatic closing of open cartons consisting of a carton body comprising a bottom panel, side walls, and a front and a back wall connected to the bottom panel; a carton cover hinged to said back wall, and front and side flange panels connected to the top panel, which carton in the collapsed condition has its cover side flange panels outfolded and its cover front flange panel infolded; and automatic locking means comprising a lock flap hinged to the front wall, and abutment means on the front flange panel, the machine comprising, in combination, an endless conveyor having lugs thereon adapted to engage said side walls; a sweep along the path of said conveyor for engaging and downfolding said cover into carton closed position; a first stationary arm yieldably mounted

30 for engaging and bearing against the leading side flange panel and a second movable arm for engaging and bearing against the trailing side flange panel during the engagement of the cover by said sweep; and means operating in timed

35 relationship with said conveyor for moving said second arm in the direction of advance of said conveyor.

40 4. A machine for the automatic closing of open cartons consisting of a carton body comprising a bottom panel, side walls, and a front and a back wall connected to the bottom panel; a carton cover hinged to said back wall, and front and side flange panels connected to the top panel, which carton in the collapsed condition has its cover side flange panels outfolded and its cover front flange panel infolded; and automatic locking means comprising a lock flap hinged to the front wall, and abutment means on the front flange panel, the machine comprising, in combination, an endless conveyor having lugs thereon adapted to engage said side walls; a sweep along the path of said conveyor for engaging and downfolding said cover into carton closed position; a first stationary arm yieldably mounted

45 for engaging and bearing against the leading side flange panel and a second movable arm for engaging and bearing against the trailing side flange panel during the engagement of the cover by said sweep; and means operating in timed

50 relationship with said conveyor for moving said second arm in the direction of advance of said conveyor.

55 5. A machine for the automatic closing of open cartons consisting of a carton body comprising a bottom panel, side walls, and a front and a back wall connected to the bottom panel; a carton cover hinged to said back wall, and front and side flange panels connected to the top panel, which carton in the collapsed condition has its cover side flange panels outfolded and its cover front flange panel infolded; and automatic locking means comprising a lock flap hinged to the front wall, and abutment means on the front flange panel, the machine comprising, in combination, an endless conveyor having lugs thereon adapted to engage said side walls; a sweep along the path of said conveyor for engaging and downfolding said cover into carton closed position; a first stationary arm yieldably mounted

60 for engaging and bearing against the leading side flange panel and a second movable arm for engaging and bearing against the trailing side flange panel during the engagement of the cover by said sweep; and means operating in timed

65 relationship with said conveyor for moving said second arm in the direction of advance of said conveyor.

66 6. A machine for the automatic closing of open cartons consisting of a carton body comprising a bottom panel, side walls, and a front and a back wall connected to the bottom panel; a carton cover hinged to said back wall, and front and side flange panels connected to the top panel, which carton in the collapsed condition has its cover side flange panels outfolded and its cover front flange panel infolded; and automatic locking means comprising a lock flap hinged to the front wall, and abutment means on the front flange panel, the machine comprising, in combination, an endless conveyor having lugs thereon adapted to engage said side walls; a sweep along the path of said conveyor for engaging and downfolding said cover into carton closed position; a first stationary arm yieldably mounted

70 for engaging and bearing against the leading side flange panel and a second movable arm for engaging and bearing against the trailing side flange panel during the engagement of the cover by said sweep; and means operating in timed

ond movable arm driven in the direction of advance of said conveyor for engaging and bearing against the trailing side flange panel during the engagement of said cover by said second sweep.

4. A machine for the automatic closing of open cartons consisting of a carton body comprising a bottom panel, side walls, and a front and a back wall connected to the bottom panel; a carton cover hinged to said back wall, and front and side flange panels connected to the top panel, which carton in the collapsed condition has its cover side flange panels outfolded and its cover front flange panel infolded; and automatic locking means comprising a lock flap hinged to the front wall, and abutment means on the front flange panel, the carton having crease lines extending across the side walls and the side flange panels permitting folding of the carton blank into flat collapsed condition, the machine comprising, in combination, an endless conveyor having lugs thereon adapted to engage said side walls and maintain said side walls in carton erected position; a first sweep along the path of said conveyor for engaging and downfolding said lock flap towards said front wall about said fold line; a second sweep along the path of said conveyor for engaging and downfolding said cover over said folded lock flap into carton closed position; a first yieldable arm for bearing against the leading side flange panel to maintain said panel in carton erected position and a second movable arm for bearing against the trailing side flange panel during the engagement of the cover by said sweep; and means operating in timed relationship with said conveyor for moving said second arm in the direction of advance of said conveyor.

5. A machine for the automatic closing of open cartons consisting of a carton body comprising a bottom panel, side walls, and a front and a back wall connected to the bottom panel; a carton cover hinged to said back wall, and front and side flange panels connected to the top panel,

which carton in the collapsed condition has its cover side flange panels outfolded and its cover front flange panel infolded; and automatic locking means comprising a lock flap connected to the front wall along a fold line; and abutment means on the inside of said front flange panel adapted to interlock with an edge of said lock flap, the carton having crease lines extending across the side walls and the side flange panels permitting folding of the carton blank into flat collapsed condition, the machine comprising, in combination, an endless conveyor having lugs thereon adapted to engage said side walls and maintain said side walls in carton erected position; a first sweep along the path of said conveyor for engaging and downfolding said lock flap towards said front wall about said fold line; a second sweep along the path of said conveyor for engaging and downfolding said cover over said folded lock flap into carton closed position; a first yieldable arm for bearing against the leading side flange panel, and a second movable arm for engaging and bearing against the trailing side flange panel during the engagement of the cover by said second sweep; and means operating in timed relationship with said conveyor for moving said second arm in the direction of advance of said conveyor.
